2,615,968

TWO-TONE AIR WHISTLE

Joseph L. Bonanno, Madison, N. J., assignor to
 The Lionel Corporation, New York, N. Y., a
 corporation of New York

Application November 6, 1948, Serial No. 58,660

7 Claims. (Cl. 177—8)

1

The present invention relates to two-tone air whistles and is more particularly directed to whistles suitable for use on toy trains and the like. Whistles heretofore made for such purpose, such, for example, as that shown in Giaimo Patent 2,145,652, have employed a small electric motor operating a blower to produce a blast of air which enters into a metal resonator. The motor and control relay were supported through a mounting connected to the resonator.

The present invention contemplates whistles for such purposes having an all plastic body forming the resonating chambers and air chest and wherein such plastic body is supported from metal elements which form parts of the motor unit. According to the present invention, a pre-assembled motor unit having the usual field and armature and carrying the impeller is employed as a support for the resonating chambers and air chest, thereby making it unnecessary to rely upon the light weight plastic parts for purposes of support.

The present invention is particularly well adapted for two-tone air whistles and when made up in the form of two-tone air whistles, such whistles employ a plastic body having two resonating chambers and a chamber for the impeller, the resonating chambers are covered by plastic members cemented in place and the air chest chamber is covered by a plate which forms part of the motor unit.

Where the device is one adapted to be controlled by a relay, the relay is according to the present invention, conveniently carried on one of the covers for a resonating chamber.

Other and further objects will appear as the description proceeds.

The accompanying drawings show, for purposes of illustrating the present invention, an embodiment in which the invention may take form, it being understood that the drawings are illustrative of the invention rather than limiting the same.

In the accompanying drawings:

Figure 1 is a top elevational view of the complete whistle unit with relay;

Figure 2 is a side elevational view of the same;

Figure 3 is a side elevational view showing the motor unit, the relay unit and the component plastic parts separated;

Figure 4 is a top plan view of the plastic body; and

Figure 5 is an inverted plan view of the mounting plate and impeller forming part of the blower unit.

2

A convenient form of blower unit is illustrated in the drawing. It has a metal plate 10 and field structure 11, field windings 12, brush rigging 13, armature 14, armature shaft 15, and radial-bladed impeller 16. This motor unit may be completely pre-assembled and tested. Where the whistle is to be of the remote control type used in toy railroads, it may employ a relay 20 similar to the relay shown in the Giaimo patent above referred to and in my prior Patent 2,155,343 of April 18, 1939.

The plastic body for the whistle is shown generally at 30. It is made in the form of a plastic molding and is of generally rectangular shape as shown in the drawing. The bottom 31 has a central opening 32. Side walls 33 extend upwardly from the periphery of the bottom 31 and immediate walls 34 extend across the body on opposite sides of the hole 32. Portions of these walls 34 are cylindrical as indicated at 35, 35. The walls 34 are connected to the walls 33 at the end only, so as to leave a discharge opening 36, 36. The outside walls 33 are provided with lipped openings 37 just beyond the discharge openings 36, 36. On the right end of the molding 30, it is provided with partitions 38 and 39 and at the left end it is provided with a partition 40.

The plastic molding 30 is provided with a stepped recess 41 shown in Figure 4, above and to the right of the opening 32, and a laterally opening recess 42 diagonally opposite. Openings 43 and 44 for screws are below the recesses. The plate 10 forming part of the blower unit has a tapped stud 44 adapted to enter the opening 43 and a tapped lug 45 adapted to enter the recess 42. Screws 46, 46 extend through the holes 43 and 44 and are threaded into the lugs 44 and 45 so as to secure the plastic body to the metal plate 10. This metal plate forms a cover for the central portion of the plastic body, and when the motor unit is in place the impeller 16 is in the air chest formed by the central chamber.

The right resonating chamber is covered by a plastic plate 50 preferably cemented in place. This plate is in the form of a bracket and has an upwardly extending element 51 adapted to support the relay 20 by a screw indicated at 52. The resonating chamber at the left is closed by a small cover 53 also cemented in place.

The metal plate 10 of the motor unit is provided with two tapped holes 54 and 55, Fig. 2, adapted to receive screws 56, whereby the entire whistle unit can be secured to an extraneous support such as 57 without imposing any strain whatever on the plastic parts.

In operation, the energization of the relay effects the closing of the circuit for the motor. The motor operates the blower and produces a blast of air which enters each of the resonating chambers so that a two-tone whistle signal is produced.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In a two-tone air whistle, a resonator comprising a molded plastic body having upwardly extending peripheral side walls, a bottom wall closed except for an inlet opening, and transverse walls located on opposite sides of the opening to form a central chamber and two end chambers, the transverse walls extending from one side wall nearly to the opposite side wall to form discharge openings from said central chamber, the side walls beyond the discharge openings having lipped openings opposite the discharge openings, plastic plates covering the end chambers, and means to cover the central opening.

2. In a two-tone air whistle, a resonator as claimed in claim 1, wherein the transverse walls are in part cylindrical to cooperate with the rotor of a centrifugal blower in the central chamber.

3. In a two-tone air whistle, a resonator as claimed in claim 1, having partitions in the resonating chambers to increase the length of the resonating air column.

4. A two-tone air whistle comprising a plastic body having two resonating chambers, each having a closed bottom and continuous side walls except for a lipped opening and for an inlet opening adjacent the lipped opening, and an intermediate chamber between the resonating chambers, and into which the inlet openings for the resonating chambers open, the intermediate chamber having cylindrical side walls and a centrally apertured bottom wall, a blower unit having a mounting plate closing the top of the intermediate chamber and an impeller in the intermediate chamber, and plastic closure plates for the resonating chambers and cemented to the plastic body.

5. An air whistle adapted for mounting to an extraneous support, comprising a power unit including a flat mounting plate, an electric motor secured to one face of the plate and having an armature shaft extending through the plate, an impeller carried by the shaft, and a plastic body secured to the mounting plate, the body having a chamber about the impeller closed by the plate and provided with an inlet and two outlet openings forming a wind chest, and two resonating chambers each communicating with an outlet opening and having lipped discharge openings, the mounting plate having mounting devices for securing it to the extraneous support.

6. An air whistle comprising a power unit including a mounting plate, an electric motor secured to one face of the plate and having a shaft extending through the plate and an impeller carried by the shaft and having radial blades, and a molded plastic whistle body secured to the mounting plate and having a chamber closed by the mounting plate, side walls shaped to fit about the impeller and air inlet opened opposite the end of the shaft and a discharge opening, and a second resonating chamber into which the discharge opening communicates, the second chamber having a side wall with an opening adjacent the discharge opening, and a molded plastic cover for the second chamber.

7. A whistle unit for toy trains comprising a motor operated blower unit having mounting brackets for securement to an extraneous support, a molded plastic body secured to the blower unit, the body having two resonating chambers closed except for lipped openings and a blower chamber communicating with the resonating chambers and having an air inlet opening, and a relay unit for controlling the motor and carried on the body.
